(57) **CLAIM**

The ornamental design for a closure for package or container, as shown.

DESCRIPTION

FIG. 1 is a bottom view of the closure according to the invention;

FIG. 2 is a side view of the closure;

FIG. 3 is another side view of the closure; and,

FIG. 4 is a top view of the closure.

The broken lines in the drawings depict environmental subject matter only and form no part of the claimed design.
